UNITED STATES PATENT OFFICE.

GAETANO FERIANI, OF BELLUNO, ITALY, ASSIGNOR TO SOCIETA BREVETTI FERIANI, OF ROME, ITALY.

INTERNAL-COMBUSTION ENGINE.

Application filed January 30, 1920. Serial No. 355,216.

To all whom it may concern:

Be it known that I, GAETANO FERIANI, a subject of the King of Italy, and resident of Belluno, Italy, have invented certain new and useful Improvements in Internal-Combustion Engines, of which the following is a specification.

The present invention relates to improvements in internal combustion engines, with variable stroke and more particularly to a new disposition of the parts for connecting the piston to the crankshaft.

The purpose of the invention is to obtain a constant horse power from internal combustion engines, a matter of great importance in motor vehicles, as it permits the elimination of the usual power transmission devices, for example, the change gear boxes.

20 The invention is featured by a new disposition of the parts of an internal combustion engine, which disposition permits of obtaining a variable stroke of the piston, and in the meantime a compression space proportional to the compression stroke,—that is, a compression adapted to maintain the horse power of the engine constant irrespective of the stroke of the piston.

For a better understanding of the invention, reference should be had to the accompanying drawings, in which:

Fig. 1 is a front elevation of one cylinder engine, partly in section, according to the present invention;

35 Fig. 2 is a side elevation of Fig. 1;

Fig. 3 is a part-sectional side elevation of a four cylinder engine, according to the invention;

Fig. 4 is a front elevation of Fig. 3;

40 Fig. 5 is a detail showing the arrangement of the oil pump;

Fig. 6 is a detail showing the controlling means;

45 Figs. 7, 8, 9 and 10 are diagrammatic views demonstrating the working of the piston.

Referring to the drawings and particularly to Figs. 1 and 2, the engine comprises a cylinder 1, provided as usual with a water jacket. Within the cylinder is fitted a piston 2 provided with a hollow stem 3. The piston 2 during its alternate motion is guided by a rod 4, entering into the hollow stem 3, which disposition is provided to

55 maintain the alignment between the piston and its cylinder.

The rod 4 is securely fixed to the bottom of the crank case 5.

A cross head 8 is provided at the lower end of the stem 3, said cross head supporting a pair of connecting rods 7, arranged as clearly shown by Fig. 2. The upper end of each connecting rod 7 is pivoted to a block 9 (Fig. 2), each block being slidably mounted within a slot 6' formed in an oscillatory arm 6 extending nearly horizontally at the top of the cylinder. The arm 6 is pivoted at one extremity at 15 to the head of the cylinder 1 (Fig. 1) and is curved, the center of the radius of curvature being 70 located inside the center line of the cylinder. At a convenient distance from the pivoted end of the arm 6, is pivoted the end of a second set of connecting rods 11, the lower ends 13 of which are connected to 75 the cranks 10 of the engine crankshaft. The latter, as best shown in Fig. 1, is mounted at one side of the engine, and is geared to the flywheel 36 by means of a set of gears 35. Of course the flywheel can be directly 80 set on the crankshaft.

The displacement and the arrest of each block 9 from one position to any other along the corresponding arm 6, is obtained by means of a threaded rod 18 on which the 85 block is mounted to travel. One end of the rod 18 bears a worm gear 17 engaging the adjacent end of a second threaded rod 16 (Fig. 2). The rotation of the rod 16 produces the rotation of the two rods 18, and as the latter 90 are fixed with relation to the blocks 9, said blocks will be moved along the slots in the arms 6, to occupy any position in the same.

From a perusal of Fig. 1, the working of the engine will be apparent. In fact the 95 stroke of the piston 2 will vary from a minimum —*f*— to a maximum —*g*—, according to the position of the slideable blocks 9 upon the arms 6—that is, from the position —*a*— to position —*b*—. The positions —*a*— 100 —*a'*—, and —*b*— —*b'*— indicate respectively the positions of the connecting rods 7, for the shorter stroke of the piston 2 (in full lines) and for the longest stroke of said piston (in dotted lines).

105 Of course the stroke of the connecting rods 11 will remain constant, as the heads 12 and 13 are respectively pivoted at fixed

points upon the arms 6 and at the cranks 10 of the engine shaft. Also the compression space will vary with the stroke of the piston 2. This function is clearly shown 5 by Figs. 7, 8, 9 and 10; in which Fig. 7 shows the compression space and Fig. 8 the corresponding stroke, and Figs. 9 and 10 the increased compression space for the corresponding increased stroke.

10 It is also evident that with the connecting rod 7 in the position shown in Figs. 7 and 8, that is with the piston performing its shorter stroke, the power transmitted to the crank 10 is a function of the distance of the 15 point $-a-$ from the center $-O-$ of oscillation of the arm 6, multiplied by the stroke of the piston in that position of the rods. By moving the connecting rod 7 from $-a-$ to $-b-$, there is an increase of power be- 20 cause of the increased value given by the product of the distance $o-b$, and the stroke of the piston. In this position of course there is a reduction of speed of the crank 10, which reduction is compensated by the in- 25 creased power. And vice versa, with the connecting rod 7 in the position shown in Figs. 7 and 8, the speed of the motor will be increased with a corresponding reduction of the stroke, but the result in both cases is a 30 constant horse power value at the crank shaft.

This happens for any position of the connecting rod 7 along the arm 6.

There is thus obtained a constant horse 35 power value at the crankshaft for any number of revolution, which of course will be determined by the position of the connecting rod 7.

This will result in great advantage for 40 motor vehicles provided with internal combustion engines as it permits a great flexibility of the engine to be obtained with a nearly complete elimination of the change gear devices.

45 Figs. 3 and 4 show a four cylinder engine designed for automobiles, the only difference from the one shown in Figs. 1 and 2 being that the arm 6, instead of being pivoted at one end to the heads of the cylinders, are 50 pivoted at an intermediate point, the connecting rods 11 being connected to the free ends of said arms.

Fig. 6 shows the means for controlling the 55 position of the connecting rods 7 and fixing them at any point along the arms 6. —20— is a pedal, formed with a toothed sector or rack 21, engaging a pinion 22. A wheel 23, in fixed relationship with the pinion 22, is connected by any convenient means, say a 60 chain 24, to a sprocket 25, journaled in a bearing 26 fixed to the dashboard of the vehicle. The hub of the sprocket 25 is threaded to receive the threaded rod 16. The latter engages the worm gear 17 (Fig. 1) 65 formed at the end of the rod 18.

By depressing the pedal 20, there is produced a rotation of the rod 18, thus moving the connecting rods 7 along the arms 6. To obtain a very rapid rotation of the rod 18, the rod 16 is doubly threaded, the direction, 70 of the said threads being opposed, as clearly shown in Fig. 6.

Fig. 5 shows the lubricating pump built in each piston. On account of the very long stroke, a very effective lubrication is necessary, and this is obtained by the arrangement shown. The guide rod 4 is bored at 28, the opening being closed by any type of valve 29. The hollow stem 3, is also provided with a valve 31, and communicates by 75 means of the duct 32 with the outer surface of the piston 2. A second passage 30 communicates with the cross head 8. The reciprocating movement of the piston 2 and of its stem 3 relatively to the rod 4 draws oil from 80 the crank case 5 sending it to the cylinder and to the cross head 8, thus attaining a 85 perfect lubrication.

Having now particularly described and ascertained the nature of my invention and 90 in that manner the same is performed, what I claim is:

1. In an internal combustion engine of the variable stroke constant power type, the combination of one or more cylinders, a piston associated with each cylinder, a fixed tubular guide secured in the stem of each piston, a cross head at the end of the piston stem, connecting rods pivoted to the cross head, two slotted oscillating levers between 95 said rods, and a block slidably mounted in the slot in each lever; one end of each of said rods being connected to the adjacent block.

2. In an internal combustion engine of the variable stroke constant power type, an oscillating arm mounted at an intermediate point upon the head of the cylinder and provided in one arm with a slot, a block slidably mounted in said slot, a cross-head at the end of the piston stem, a rod connecting the block to the cross head, and means for moving the block along said slot.

3. In an internal combustion engine of the variable stroke constant power type, an oscillating lever pivoted at an intermediate 115 point to the head of the engine cylinder, a rod connecting one arm of said lever to the piston of the engine, and a second rod connecting the other arm of said lever to the crank shaft of the engine, the said second connecting rod being pivoted to the oscillating lever at a fixed point thereon.

4. In an internal combustion engine of the variable stroke constant power type, an oscillating lever pivoted at an intermediate 120 point to the cylinder head, a block slidably mounted on one arm of said lever, means connecting said block to the piston of the engine, means connecting said lever at one point of the other arm thereof to the crank 125 130

shaft, and means for varying the position of the slidable block along said oscillating lever.

5. In an internal combustion engine of the type described, the combination of a cylinder, an oscillating arm pivoted at an intermediate point to the head of the engine cylinder and provided in one arm with a slot, a fixed tubular guide secured at one end to the 10 crank case, and telescoping at the other end in the piston stem, a cross head at the end of the piston stem, a rod connecting the block

to the cross head, means for moving the block along said slot, and means for lubricating the piston and the cross head comprising said fixed guide and piston stem. 15

In testimony whereof I have hereunto signed my name in the presence of two witnesses.

GAETANO FERIANI.
